UNITED STATES PATENT OFFICE.

EMMETT TEELETON COX, OF MCKENNEY, VIRGINIA.

SPARK-ARRESTER.

1,200,816.

Specification of Letters Patent.

Patented Oct. 10, 1916.

Application filed February 12, 1914, Serial No. 818,254. Renewed August 18, 1916. Serial No. 115,695.

To all whom it may concern:

Be it known that I, EMMETT T. COX, residing at McKenney, in the county of Dinwiddie and State of Virginia, have invented 5 certain new and useful Improvements in Spark-Arresters, of which the following is a specification.

My invention has for its object to provide a practical and efficient mechanism for 10 arresting and extinguishing the sparks from smoke-stacks of any kind, viz.—those employed on locomotives, steam boats, stationary boilers, heating furnaces, or in fact, any stack through which smoke and sparks are 15 discharged.

Generically, the invention provides means for closing the stack (when the stack is the ordinary open one) and drawing off the 20 products of combustion by a suction fan, discharging the products of combustion at some predetermined place, and, when found desirable, first passing the products of combustion through a baffle box to arrest and extinguish any fire that may be present 25 therein, supplementing such baffle box by a water spray, if found necessary.

In its more subordinate nature, the invention also embodies those novel details of construction, combination and arrangement of 30 parts, all of which will be first fully described, and then pointed out in the appended claims, reference being had to the accompanying drawings, in which:—

Figure 1 is a perspective view illustrating 35 the application of the invention to a locomotive. Fig. 2 is an enlarged detail side elevation of one of the fans or blowers. Fig. 3 is a top plan view of the same. Fig. 4 is an enlarged sectional view of the baffle 40 box and water spraying device, and showing the connection of the same with the distributing union through which the condensation products are also adapted to be separated. Fig. 5 is a detail horizontal section through one of the valves shown in Fig. 45. Fig. 6 is a detail perspective view illustrating one way of providing a cover for the stack. Fig. 7 is a detail view showing one way of holding the smoke-stack cover 50 to its adjustments.

In the drawings, in which like letters and numerals of reference indicate like parts in all of the figures, 1 represents the boiler and 55 2, the stack (it being understood that the boiler and stack may be of any type). If the stack 2 is normally an open one, such as

is employed on a locomotive, I provide it with a cover 4 that is hinged at 5 to brackets 3, and it is adapted to be opened through the medium of a pull rope 7 and lever 6, and closed by a spring 8, as indicated in Fig. 6 of the drawings. The rope 7 may be provided with a hook 9 and secured to a pin 10 in the engineer's cab, when it is desired to hold the cover 4 in its open position. It 65 should be understood that this is desirable when the locomotive is standing still and the blower (hereinafter referred to) is not operating.

Secured at the sides of the stack 2 are 70 offtake pipes 11 which convey the products of combustion to the blowers 12 (there being usually two blowers employed, one on each side of the locomotive, when the invention is employed on locomotives). The 75 blowers 12 are each provided with a driving shaft 13 and are driven, in the case of the locomotive use, from a moving part, such as the front truck wheels, through the medium, for example, of a belt 14 and pulleys 80 15, or in any other preferred way, the pulley 15 on the shaft 13 of the blower being loose and adapted to be secured to turn with the shaft by a suitable clutch element 16 that is operated by lever 17, and rod 17^a 85 which projects into reach of the engineer. The discharge 18 of the blower preferably delivers into a baffle box 19 in which the baffles 20 serve to interrupt the passage of the solid matter, such as sparks and cause 90 them to deposit in the bottom of the box. Any sparks which pass through the box are extinguished in the duct 21 by the water spray from a nozzle 22, it being understood that the water spray is not used unless it is 95 found that the box 19 is insufficient to extinguish the sparks completely.

23 is the "bell" into which the duct 21 discharges and the "bell" 23 is provided with a plurality of offtakes 24, 25 and 26, 100 the latter one of which may be coupled to a pipe 27 which can run under the cars and discharge at the rear of the train. The offtake 25 may extend up and discharge over the top of the first or baggage car, while 105 the offtake 24 may be used to discharge directly toward the ground at the rear of the tender, it being understood that suitable valves 28 are employed in the various ducts 24, 25 and 26. The "bell" 23 may be left 110 open at its forward end so that the water from the spray nozzle 22 may drop out

instead of passing through the various discharges 24, 25 and 26, the "bell" 23 and duct 21 acting as an ejector by virtue of their correlative arrangement.

5 I have not illustrated the application of my invention to a steam boat smoke-stack, as its application will be obvious from what has heretofore been said.

By the use of my invention, not only are 10 the sparks arrested, but the smoke is largely suppressed and when the invention is used in cities on smoke-stacks of manufacturing plants or stationary engines, the products of combustion may be directly discharged 15 into the sewers and thus not vitiate the atmosphere.

From the foregoing description, taken in connection with the accompanying drawings, it is thought the complete construction, 20 combination and arrangement of parts will be fully understood by those skilled in the art to which the invention relates, and I desire it understood that changes in the details of construction and arrangement of 25 parts may be made without departing from the spirit of the invention set forth in the following claims.

What I claim is:

1. In combination with a smoke stack 30 and means for drawing off the products of combustion, of a baffle box into which said products of combustion are discharged by said drawing off means, said baffle box including means for retarding the sparks, a 35 distributing bell, a pipe leading from said baffle box into the open end of said bell, a ring around said pipe supporting it within said bell, means for admitting water into said pipe to extinguish any sparks that pass 40 through the baffle box, said bell having provision for draining the water out of the same at its open end, a plurality of off-takes from the closed end of said bell and control valves in said off-takes whereby any one or more of 45 said off-takes may be opened or closed, as desired.

2. In a spark arrester, the combination with a stack, of means for drawing the products of combustion from the stack, a 50 baffle box into which said means delivers the products of combustion, a discharge duct from said baffle box, a receiving bell into which said duct discharges, and a plurality of offtakes from said receiving bell through 55 all or any one of which the discharged products may be directed to pass, and valves in said offtakes for controlling the passage through the same.

3. In combination with the smoke-stack 60 of a locomotive; of a cover therefor, means under control of the engineer for manipulating said cover, a blower fan mounted on the engine, a pipe connection between the intake of said fan and said stack, said fan 65 including an operating shaft, power trans-

mitting connections between one of the wheels of the locomotive and the fan shaft, said connections including a clutch device, and means under the control of the engineer for operating said clutch device, a discharge duct from said blower fan, said discharge duct delivering downwardly and rearwardly beneath the train, substantially as shown and described.

4. In combination with the smoke-stack 75 of a locomotive; of a cover therefor, means under control of the engineer for manipulating said cover, a blower fan mounted on the engine, a pipe connection between the intake of said fan and said stack, said fan including an operating shaft, power transmitting connections between one of the wheels of the locomotive and the fan shaft, said connections including a clutch device, means under the control of the engineer for operating said clutch device, a discharge duct from said blower fan, said discharge duct 80 delivering downwardly and rearwardly beneath the train, a baffle box mounted under the tender into which said discharge duct 85 delivers the products of combustion, said baffle box having an outlet.

5. The combination with the smoke-stack 95 of a locomotive; of a cover therefor, means under control of the engineer for manipulating said cover, a blower fan mounted on the engine, a pipe connection between the intake of said fan and said stack, said fan including an operating shaft, power transmitting connections between one of the 100 wheels of the locomotive and the fan shaft, said connections including a clutch device, means under the control of the engineer for operating said clutch device, a discharge duct from said blower fan, said discharge 105 duct delivering downwardly and rearwardly beneath the train, a baffle box mounted under the tender into which said discharge duct delivers the products of combustion, said baffle box having an outlet, and means 110 for receiving the discharge from said baffle box outlet and directing the same to a predetermined place for discharge into atmosphere.

6. In combination with the smoke-stack 115 of a locomotive; of a cover therefor, means under the control of the engineer for manipulating said cover, a blower fan mounted on the engine, a pipe connection between the intake of said fan and said stack, said 120 fan including an operating shaft, power transmitting connections between one of the wheels of the locomotive and the fan shaft, said connections including a clutch device, means under the control of the engineer for 125 operating said clutch device, a discharge duct from said blower fan, said discharge duct delivering downwardly and rearwardly beneath the train, a baffle box mounted under the tender into which said discharge 130

duct delivers the products of combustion, said baffle box having an outlet, means for receiving the discharge from said baffle box outlet, and directing the same to a predetermined place for discharging into atmosphere, said last named means comprising a distributing bell, and a plurality of

outlet ducts from said bell with valves in said ducts for controlling the passage through the same.

EMMETT TEELOT COX.
